UNITED STATES PATENT OFFICE.

LESLIE M. HARRIMAN, OF LYNN, MASSACHUSETTS.

TORPEDO GUARD FOR VESSELS.

1,413,270.

Specification of Letters Patent. Patented Apr. 18, 1922.

Application filed July 5, 1921. Serial No. 482,556.

To all whom it may concern:

Be it known that I, LESLIE M. HARRIMAN, a citizen of the United States, residing at Lynn, in the county of Essex and State of Massachusetts, have invented certain new and useful Improvements in Torpedo Guards for Vessels, of which the following is a specification, reference being had therein to the accompanying drawings.

10 My present invention relates to certain new and useful improvements in guards employed by vessels and the like to protect their hulls against injury by planted mines or by torpedoes discharged thereagainst.

15 Marine torpedoes of the type at present employed are generally provided with a nose or contact cap which functions on striking objects, such as the side of vessels, to set off the explosive charge contained within the

20 torpedo body or are provided with mechanism, so arranged, that the stopping of the torpedo by coming in contact with the obstacle sets the mechanism in operation to set off the explosive charge carried by the

25 torpedo. My invention is designed to prevent or minimize the effects of the explosion of such torpedoes discharged at the hull of a vessel. Broadly, this invention involves the provision of the hull with a structure

30 which is normally closely held adjacent the outer face of the hull of the vessel and is adapted when in danger zone to be outriggered or spaced apart from the hull so that the hull is protected from any explosion by

35 the guard and by the wall of water between the guard and the hull.

Further, the outriggered structure is provided with many openings which are adapted to receive the tapered nose or cap-end of

40 the torpedo and yet are not large enough to permit the entrance of the torpedo body. The portions of the guard adjacent the openings are beveled so that they provide substantially knife edges and thus present a

45 smaller object to the direct path of the projected tapered nose torpedo.

My invention is designed also to prevent a mine, of that type set off by contact with a vessel, exploding beneath the hull, but being caused to explode in the water away from the hull by having been set off by contact with the front of the guard, so that the explosive force against the hull is minimized by the wall of water between the guard and

55 the hull.

The object therefore of this invention is to provide a mine and torpedo guard for vessels.

A further object is to provide a torpedo guard for vessels which may be carried by 60 a vessel and spaced apart from the hull and its sides movable to a normal position adjacent the outer face of the hull so that the frictional retardation of the moving vessel is reduced, but having its bow extending 65 forward of the bow of the vessel approximately the same distance to meet planted mines as when in its outriggered position.

It is also my aim to provide such a device of the very simplest construction, free 70 from complications, with all parts made with V-shaped edges minimizing retardation, with hollow parts ensuring buoyancy, and all so arranged that it will at all times ensure efficiency of service.

The invention consists in certain novel features of construction and arrangement of parts which will be fully understood by reference to the description of the drawings and to the claims hereinafter given.

Referring to the accompanying drawings: Figure 1 is a plan view of my guard attached to a vessel, when in its outermost position ready to meet a torpedo. Fig. 2 is a side elevation of my guard attached to a 85 vessel. Fig. 3 is a rear elevation of the same. Fig. 4 is a plan view of the same in a closed position. Fig. 5 is an enlarged sectional elevation of an upper portion of the guard.

Similar characters designate like parts throughout the several figures of the drawings.

Latitude is allowed herein as to details, as they may be changed or varied at will without departing from the spirit of my invention and the same yet remain intact and be protected.

This novel torpedo guard comprises broadly a device which extends preferably 100 on the bow and sides of a vessel or other craft. The stern is not usually required to be guarded as attacks in the rear are difficult and rare but to guard it requires only a duplication of the bow structure. The 105 guard structure is so made that it occupies a position normally adjacent the outer face of the three mentioned portions of the hull, while it is movable to assume an outriggered position spaced apart from the hull so that 110

- torpedoes may be stopped when still away from the hull and while the force of an unchecked or accidental explosion will be minimized by the water intervening between the 5 hull and the guard. The guard can be shaped to conform substantially to the longitudinal lines of the hull and extends, in this selected embodiment, from just below the water line to the horizontal plane of the 10 keel or to a slight distance below the same. The guard is articulated so that in its movements from normal to operative position and vice versa, the longitudinal lines of the hull may be correspondingly maintained.
- 15 Commencing at the top near the water line and extending therebelow are a plurality of longitudinal openings which are large enough to permit the entrance of the usual tapered nose of a torpedo but not the 20 torpedo body.

In the embodiment of the invention here illustrated there is shown the hull, designated by the numeral 6, of a vessel which may, of course, be of any length and any desired shape. The guard members on each side of the hull are preferably formed of articulated sections, the length and number of same being according to the length of the vessel. The bow sections 7 are pivotally 25 connected to and supported by the forward side sections 10 as by means of the headed pivot rods 8. The two complementary bow sections 7 are provided on their outer edge with hinges 9, about which they may turn in 30 the manipulation of the guard; the arrangement of the hinges on the bow sections being so arranged, that if desired, by removing the links on one side of the guard from the vessel, that side of the guard can be swung 35 around to the other side of the guard forward of the same, and allow the vessel to be swung in and alongside of a wharf or about another vessel. The bow sections 7 and the side sections 10, 11, 12, and 13 are substantially 40 equal in depth and extend as far as the keel of the protected hull or can be extended to a greater depth if deemed advisable. The bow sections and the side sections are preferably 45 below the water line but if desired 50 they can be extended above the water line to form a protection for the upper part of the hull against shot, and the bow sections can be inclined upward to a greater height than the side sections as clearly shown in Fig. 2.

55 In this embodiment of my invention, pivoted connection of the side sections 10, 11, 12, and 13 to the hull 6 is afforded by means of upper links 15 and lower links 26. Each link is pivotally mounted at each end and for 60 this purpose, pairs of lugs are formed on the outer face of the hull and inner face of the side members; the lugs formed on the upper outer face of the hull being designated by the numeral 17 while the lugs formed on 65 the lower outer face of the hull being design-

nated by the numeral 27, these lugs being provided with outwardly extending arms in the outer ends of which the links 15 and 26 are pivotally mounted, and the lugs formed on the inner face of the side members being 70 designated by numeral 16 for the upper one and by numeral 29 for the lower one.

These links are preferably employed in superposed pairs. As shown in this embodiment eight links are employed on each side 75 of the hull but it is to be understood that the number or arrangement of the linking structure may be varied to accord with the type and side of the hull; also that the length of the arm on the lugs 27 depends entirely on 80 the inward sweep of the underpart of the hull. It also may be found desirable, as the inward sweep of the hull is very slight compared with the length of the links, which would ordinarily be upward of twelve feet, 85

to slot the link at one or both ends to allow free play and movement as the guard is closed or opened, and thus do away with the outward extending arm of the lugs 27 between the end 28 and the side of the vessel 6. 90

The lugs are preferably formed so as to give as little resistance as possible, and wherever possible, for the same purpose, all parts that would cause retardation of the vessel are made with knife or V-shaped edges. As shown 95 in Fig. 2 the guard extends from adjacent the bow of the vessel's hull to substantially beyond the stern of the same and consists of the bow section 7 connected to the forward side sections 10 by means of the pivot rods 8, 100

and supported in place by these side sections 10; the sections 10 being pivotally connected with the intermediate sections 11 by means of the headed pivot pin 14, and in a vessel of any length there would be a series 105 of these intermediate sections 11, secured to one another in the series by pivot pins 14, as for example, as in Fig. 1, sections 11 to 10, 12 to 11, and 13 to 12. The bow sections 7 and each of the side sections are preferably 110 formed with a hollow top, as shown in Fig. 5, reinforced by an upright support or brace 19 and a cross brace 20, with a series of parallel hollow rods, which may be of a construction to make them air tight, designated 115 by the numeral 25, each having a standard or support 23 extending from its lower V-shaped side to its uppermost portion. These rods being so constructed that a sectional view through the same would show, as in 120 Fig. 5, a diamond shaped construction. The distance from outer point to the center of the support 23 being 6 inches and the distance from the inner point to the center of the support 23 being 4 inches, making a total 125 width of only 10 inches, and by examination of Fig. 5 it will be seen that the standard supports 19 and 23 are towards the inner face of the guard.

These hollow rods and top in the side 130

sections are connected by uprights 40; the lugs 16 and 29 being connected on the inner side of the upright portions 40. These sections constituting the guard members are 5 provided with longitudinal openings 18, which extend vertically substantially from the water line to the bottom of the sections. These openings are therefore formed of such transverse width as to permit the free 10 entrance of the tapered nose or cap of the torpedoes now in use but not the body portions thereof. From the construction of the rods, with their V-shaped forward portion, substantially knife edges are presented 15 to an oncoming torpedo. Such provision not only reduces the liability to immediate explosion of the torpedo by contact with one of these intervening portions but the angled openings tend to deflect gently and 20 guide the torpedo nose into an opening when the torpedo body will be wedged between the sides of an opening and rendered harmless.

The means, shown in the accompanying drawings, which are operable to retain the 25 sections adjacent the hull or to retain them in spaced relation therefrom, comprise a motor 30 geared to shaft 31 which has at opposite ends bevel gears 32 meshing with bevel gears 33 on shaft to which is also fast 30 pinion 34 adapted to mesh with sector 35 pivoted at 36 and said sector being fast to the rear arm 15 as indicated at 37, see Fig. 1. Said motor 30 being in electric circuit under control of switch 38. It is evident 35 that outward movement of the sectors 35 causes the guard sections to move forwardly with relation to the vessel's hull to an out-rigged position. When need for torpedo protection is absent, an inward movement 40 of the sectors 35 functions to swing the guard sections rearwardly with relation to the hull into normal position. It is also evident that the sections may be moved to any 45 desired position from the inner normal position, which may be at 12 or more feet from the hull, so that if desired to only move the sections to four or five feet distance from the vessel's side the sectors 35 are only moved outward the required distance necessary to 50 move the sections to the desired distance. It may be found desirable not to have the 55 guard sections carried forward to the position shown in Fig. 1 or it may be preferable to have the lugs 17 and 27 on the sides of the hull set forward of their corresponding lugs 16 and 29 on the inner sides of the sections to allow of readily collapsing, instead of breaking, if struck by another vessel or by a torpedo, especially if the gearing has not been locked. The striking of 60 the section by a torpedo would in the majority of cases, cause the section to move a few feet inward as the nose of the torpedo became wedged between the rods, and show 65 to the occupants of the vessel that the guard

had been struck by a torpedo. The guard is self floating, and is no load on the vessel other than the extra power required to carry it through the water, and therefore overcomes the objections to guards supported 70 from the sides of vessels. There is therefore, provided a simple, efficient and durable torpedo guard which may be inexpensively constructed, the range of permissible materials is wide and as many variations may be 75 made in the structure of the guard as are desirable to adapt it to vessels of different types.

It is to be understood that my invention is not limited to the specific details of construction shown in the accompanying drawing, but that said details may be varied in the practical carrying out of my invention. It is also to be understood that the combinations set forth in the several claims are intended to be used in connection therewith of other features and details of construction 85 illustrated.

Having thus described my invention, what I claim as new and desire to secure by Letters Patent, is—

1. A torpedo guard for vessels comprising side sections extending from adjacent the bow of a vessel's hull to substantially beyond the stern of the same, a pair of bow 95 sections, said bow sections being articulated and each having articulated connection with its adjacent side section, means for pivotally supporting the side sections from the hull to permit said sections to swing laterally from 100 and longitudinally of the hull, and means operable to retain the sections adjacent the hull or to retain them in laterally spaced relation therefrom, the articulation of the sections permitting the same to maintain substantially the longitudinal lines of the hull 105 in all positions of lateral and longitudinal movement.

2. A torpedo guard for vessels comprising a pair of hinged bow sections, a series of 110 floatable side sections, the bow and side sections forming a series of sections extending from the front of the bow of the vessel to substantially beyond the stern of the same, links pivoted at one end to the vessel's hull 115 and at the other end to the said sections, said links being at all times inclined rearwardly, and means connected with the rear set of links operable from the vessel to move the sections to a forward defensive position or 120 rearwardly to a collapsed position, substantially as shown and described.

3. A torpedo guard for vessels comprising a series of floatable side sections having 125 V-shaped edges, a pair of bow sections, said bow sections being articulated and each having articulated connection with its adjacent side section, each of said side sections being the first in a series of articulated side sections, each having articulated connection 130

- with the section in its rear, each of said side sections being pivotally supported from the hull of the vessel so that said sections swing laterally from and longitudinally of the hull 5 without strain on the hull and means operable to retain the sections adjacent the hull or to retain them in laterally spaced relation therefrom, substantially as shown and described.
- 10 4. A self floating torpedo guard comprising a series of side sections for each side of the vessel, a pair of bow sections, said bow sections being articulated and each having articulated connection with its adjacent side 15 section, said bow and side sections being hollow wherever possible and having V-shaped edges to cause cutting surfaces in the water, standards within said hollow portions, and means for holding the sections in a position 20 so arranged that the striking of a section by a torpedo will cause the sections to move rearwardly and towards the vessel to a collapsed position, substantially as shown and described.
- 25 5. A torpedo guard comprising self float-
- ing side sections, a pair of hinged self floating bow sections, said sections extending from adjacent the bow of the vessel to substantially beyond the stern of the same, said bow sections having articulated connection 30 with its adjacent side section, each of said side sections being the first in a series of articulated side sections on that side of the hull and each having articulated connection with the section in its rear, links in superposed pairs pivotally connected with the hull at one end and with the inner side of the section of the guard at the opposite rearwardly inclined end, gearing carried on the vessel for actuating the guard, sectors connecting 35 the gearing and the links of the end sections, and means for actuating the sectors to cause the guard to assume a collapsed position against the side of the hull or an outriggered position away from the hull, and the bow 40 sections so constructed as to act as mine sweepers, substantially as shown and described.
- 45 In testimony whereof I affix my signature.

LESLIE M. HARRIMAN.
